UNITED STATES PATENT OFFICE.

LARS H. VOLD, OF WESTVILLE, NEW JERSEY, ASSIGNOR TO WILLIAM SELLERS & COMPANY, INCORPORATED, OF PHILADELPHIA, PENNSYLVANIA, A CORPORATION OF PENNSYLVANIA.

LATHE-DRIVER.

No. 881,749.

Specification of Letters Patent.

Patented March 10, 1908.

Application filed April 4, 1907. Serial No. 366,381.

To all whom it may concern:

Be it known that I, LARS H. VOLD, a citizen of the United States, residing at Westville, county of Gloucester, and State of New Jersey, have invented a new and useful Improvement in Lathe-Drivers, of which the following is a full, clear, and exact description, reference being had to the accompanying drawings, which form a part of this specification.

The main object of my invention is to provide a means by which a wheel or a pair of wheels mounted on an axle centered between the centers of a wheel lathe, can be effectively secured to the face plate or face plates, and made to rotate against the resistance of a heavy cut applied to the rim of the wheel in such a manner that the gripping tendency of the driver upon the wheel adjusts itself automatically to the resistance of the cut.

It is a further object of my invention to avoid any special effort or hard labor on the part of the operator in the application of the driver to the wheel, such as would be required to handle and use heavy wrenches or sledge hammers.

It is a further object of my invention to provide a fixed open position of the driver, so that work can be placed and removed with ease, and also to combine all the parts necessary for its functions in one unit with no loose pieces to handle, and to thus avoid the risk of losing or mislaying such pieces and consequent loss of time.

I will now describe a preferred embodiment of my invention.

In the drawings: Figure 1 is a plan view of the driver. Fig. 2 is a sectional view through one of the drivers and the rim of the wheel that is to be held. Fig. 3 is a side elevation of the driver in its open position ready to receive the work, also showing in section a portion of the wheel to be held. Fig. 4 is a front view of the driver and the bracket or base that carries the driving arm.

4 is a bracket bolted to one of the face plates of the lathe.

30 is a block loosely fitted into the bracket 4 between two projecting wings 11 and 110 to which the block is pivoted by means of a bolt 5 extending through holes in the block and both wings.

1 is an arm or lever provided with a trun-

nion 32 fitting in the block 30 between a shoulder 22 on the arm and a collar or nut 20 on the trunnion. The arm 1 is curved to reach around the rim of a wheel between the arms or spokes of the wheel and is provided, at its outer end, with a set-screw 8, adjustable to and from the block 30. The axis of the trunnion 32 is perpendicular to the axis of rotation of the wheels to be turned.

The holes 12, in the wings 11 and 110, through which the bolt 5 passes, are elongated in a direction parallel to the axis of rotation of the lathe spindle, giving to the block 30, with the pieces attached thereto, a limited adjustment to and from the rim of the wheel to be turned. The bolt 5 at one end is collared by its head 19 against the outside of the wing 11, and at the other end is provided with a wedge 7 extending through its body and bearing against the wing 110 in such manner that, if desired, a clamping action can be set up between the bolt and the two wings and block 30, by driving the wedge 7. Ordinarily, however, the fit of the block between the wings is a loose one to permit the block 30 to have a free pivotal movement.

9 is a socket piece or jaw fitted and secured to the block 30 and carrying on its outer face two or more spuds or points 10 adapted to go against the rim of the wheel and embed themselves in the wheel for driving purposes.

The action of the driver, so far as described, is as follows: After a wheel is put into place, the arm 1 and block 30 are swung, on the bolt 5, from the position shown in Fig. 3 into the position shown in Fig. 2, and the driver, by means of the set-screw 8, is clamped lightly to the rim or tire B between the set screw and the spuds 10; the arm, in this position, being perpendicular to the plane of the wheel so that the projected distance between the point of the set screw and the trunnion 32 is the true distance. Motion is then imparted to the driver from the face-plate to which it is secured. When a cut is applied to the rim of the wheel, the wheel will stop and the point of the set screw 8 pressing against the wheel will also stop, while the bracket 4, block 30 and the trunnion end of the arm 1, will advance with the face-plate. The arm 1 will therefore assume an inclined

position in the direction of the arrow, Fig. 1, and the projected distance between the point of the set screw 8 and the trunnion 32 will become less than the true distance, causing the 5 spuds 10, which offer the least surface for resisting the pressure, to embed themselves in the rim of the wheel. The inclination of the arm 1 will continue until the spuds have acquired sufficient grip on the rim of the wheel 10 to overcome the cut.

When the lathe is stopped, the strain on the spuds and the driver may be relieved by slackening the set screw 8. To remove the wheel, the driving arm 1, with the block 30 15 is rotated on the pivot bolt 5, so that the free end of the arm, with its set-screw 8, can pass easily beneath the rim of the wheel and between the two adjacent spokes.

13 is a latch pivoted on the arm at 14 and 20 adapted to hook over a projection or catch 15 on the inner face of the bracket 4 when the arm is swung into the open position shown in Fig. 3. A pin 16, fixed in the side wings 11 and 110 of bracket 4, and extending across 25 the open space between the wings, affords a stop for a projection 17 on the block when the arm is swung into such open position. The bracket 4 is provided with a V-shaped socket 18 (best shown in Fig. 4) which corresponds with the lower edge of the arm at 30 that point and forms a bearing for the arm in its lowest or open position. Thus, when the arm is swung into the open position shown in Fig. 3, the latch 13 and projection 15 form a 35 stop for the motion of the arm in the direction of the arrow x , Fig. 3, and the stop 16 and projection 17, with the socket 18 in the lower part of bracket 4, limit the motion of the arm in the direction of the arrow y , 40 Fig. 3. Furthermore, the socket 18 and the trunnion 32, acting together, prevent the vibration of the arm around the trunnion 32. Thus the arm becomes locked in its open position no matter where the driver stands in relation to the axis of rotation.

To clamp the driver to the wheel, the wheel is put into position as indicated in Fig. 3, and the lathe is rotated until the driver that it is desired to lock is in such 50 position that the arm 1 will tend to swing by gravity into a horizontal position, that is, with the axis passing through 5 and 8 in a position extending perpendicular to the face plate. To permit this action to take place, 55 the latch 13 is released by pressing on, or striking, the projecting end of the latch lever and the arm 1 allowed to turn on the bolt 5 as a center until the block 30 strikes the stops 21 projecting from the inner sides of the 60 wings 11, 110, and the arm will be in the correct alignment for clamping, as hereinbefore described.

In turning upon their circumference two locomotive driving wheels mounted on their 65 axle centered between the centers of a wheel

lathe, a plurality of these drivers, say two to each face plate, would be employed for clamping the wheels.

It will be understood that the principal gripping face may be carried on the free end 75 of the arm 1 instead of on the block 30. It will also be understood that the specific construction shown is one designed for application to a wheel having spokes, which enables one of the contracting parts to be inserted 75 between the spokes and the grip applied on opposite sides of the rim. My invention, however, is not limited to the specific construction and arrangement of parts shown, whether the conditions of use be the same as 80 or different from the conditions to which the specific construction and arrangement described are applicable.

Having now fully described my invention, what I claim and desire to protect by Letters 85 Patent is:

1. A driver for work centered between the centers of a lathe, comprising a support adapted to be secured to the face-plate of the lathe, a part attached, and movable with 90 relation to said support, and having a gripping face arranged to abut against the work; and a clamping face pivotally mounted upon the gripping part and adapted to engage the work and partake of its movement and thereby 95 actuate the gripping part to embed its gripping face into the work.

2. A driver for work centered between the centers of a lathe comprising a stationary support adapted to be secured to the face-plate 100 of the lathe, a part attached to said support adapted to contact with the face of the work and movable, to increase its grip on the work, in a direction substantially parallel to the axis of the lathe, and a second part, 105 adapted to contact with the face of the work and movable in relation to said support, in a direction substantially opposite to the direction of rotation of said support, and connections between the parts, adapted to be 110 actuated by the work in its resistance to rotation by which the said movement of the second part produces the said movement of the first part, and thereby causing the first part to embed its gripping face into the work 115 until the gripping effect is sufficient to overcome the resistance to rotation.

3. A driver for work centered between the centers of a lathe, comprising two parts 120 adapted to engage the face of the work, one part having a gripping face and movable, relatively to the work, in a direction substantially parallel to the axis of the lathe, and the other part being movable, with respect to the first part, in a substantially circumferential direction in relation to the axis of rotation of the lathe, and connections between the parts actuated by the second part and adapted, during the rotation of the lathe, when the second part is moved rela- 125 130

tively to the first part by partaking of the relative movement of the work in the latter's resistance to rotation, to so actuate the first part, thereby embedding the gripping face of the first part into the face of the work.

4. A driver for wheels mounted on an axle centered between the centers of a wheel lathe, comprising two parts adapted to engage opposite faces of a wheel rim, one part 10 having a gripping face and movable, relatively to the wheel, in a direction substantially parallel to the axis of the lathe, and the other part having a clamping face and movable, with respect to the first part, in a 15 substantially circumferential direction about the axis of the lathe, and a connection between the parts adapted to extend within the rim and between the spokes of the wheel and adapted, during the rotation of the 20 lathe, to be actuated by the second part and move the first part as described, thereby embedding the gripping face of the first part into the wheel face.

5. A driver for wheels mounted on an axle 25 between the centers of a wheel lathe, comprising a support adapted to be attached to the face plate of the lathe, a part having a gripping face and pivoted to said support, a clamping part adapted to engage the wheel 30 face and partake of its movement, an arm carrying the clamping part and pivoted to the first part and adapted, when the clamping part is actuated by the wheel in the latter's resistance to rotation, to move the 35 first part toward the wheel and embed its gripping face into the wheel face.

6. A driver for wheels mounted on an axle between the centers of a wheel lathe, comprising a support adapted for attachment to 40 the face plate of a lathe, a block provided with a gripping jaw adapted to engage one face of a wheel rim and pivotally mounted on said support to permit its gripping end to swing toward and from the lathe axis, an 45 arm pivotally mounted on said block on an axis perpendicular to the axis of rotation and adapted to extend within the rim and between the wheel spokes, and a clamping part on the free end of the arm adapted to 50 engage the opposite face of the wheel rim, thereby permitting the gripping jaw and clamping part to swing radially of the rim and allowing the arm to swing in a direction 55 parallel to the axis of rotation.

5. 7. A driver for wheels mounted on an axle between the centers of a wheel lathe, comprising a support adapted for attachment to the face plate of a lathe, a block provided with a gripping jaw adapted to engage one 60 face of a wheel rim and pivotally mounted on said support to permit its gripping end to swing toward and from the lathe axis, an arm pivotally mounted on said block on an axis perpendicular to the axis of rotation 65 and adapted to extend within the rim and

between the wheel spokes, a clamping part on the free end of the arm adapted to engage the opposite face of the wheel rim, a projection on the support, a latch on the arm engaging the projection when said arm is 70 swung toward the axis of rotation and holding the arm in its open position.

8. A driver for wheels mounted on an axle between the centers of a wheel lathe, comprising a support adapted for attachment to 75 the face plate of a lathe, a block provided with a gripping jaw adapted to engage one face of a wheel rim and pivotally mounted on said support to permit its gripping end to swing toward and from the lathe axis, an arm 80 pivotally mounted on said block on an axis perpendicular to the axis of rotation and adapted to extend within the rim and between the wheel spokes, a clamping part on the free end of the arm adapted to engage 85 the opposite face of the wheel rim, and a stop on the support engaging said block and limiting the movement of the gripping jaw of the block toward the axis of rotation.

9. A driver for wheels mounted on an axle 90 between the centers of a wheel lathe, comprising a support adapted for attachment to the face plate of a lathe, a block provided with a gripping jaw adapted to engage one face of a wheel rim and pivotally mounted on 95 said support to permit its gripping end to swing toward and from the lathe axis, an arm pivotally mounted on said block on an axis perpendicular to the axis of rotation and adapted to extend within the rim and between the wheel spokes, a clamping part on the free end of the arm adapted to engage the 100 opposite face of the wheel rim, said support having a socket into which said arm extends when said block and arm are swung toward the axis of rotation, thereby limiting the movement of the arm toward the axis of rotation and holding it from turning on its pivot in a direction parallel to the axis of rotation.

10. A driver for wheels mounted on an axle between the centers of a wheel lathe, comprising a support adapted for attachment to the face plate of a lathe, a block provided with a gripping jaw adapted to engage 115 one face of a wheel rim and pivotally mounted on said support to permit its gripping end to swing toward and from the lathe axis, an arm pivotally mounted on said block on an axis perpendicular to the axis of rotation and adapted to extend within the rim and between the wheel spokes, a clamping part on the free end of the arm adapted to engage the opposite face of the wheel rim, and a stop on the support engaging the block 120 when said arm is moved into clamping position.

11. A driver for wheels mounted on an axle between the centers of a wheel lathe, comprising a support adapted for attach- 130

- ment to the face plate of a lathe and having holes elongated in the direction of the axis of rotation, a bolt extending through said holes, a block, provided with a gripping jaw, carried on said bolt, a swinging arm, a trunnion thereon, fitting in said block, whose axis is perpendicular to the axis of rotation of the wheel to be turned, and a clamping part on the free end of the arm.
- 10 12. A driver for wheels mounted on an axle between the centers of a wheel lathe, comprising a support adapted for attachment to the face plate of a lathe, and having holes elongated in the direction of the axis of rotation, a bolt extending through said holes, a block, provided with a gripping jaw, carried on said bolt, a swinging arm, a trunnion thereon, fitting in said block, whose axis is perpendicular to the axis of rotation of the wheel to be turned, a clamping part on the free end of the arm adjustable toward and from the gripping jaw, stops on the support limiting the pivotal movement of the block in opposite directions respectively, a pro-

jection on the support, and a latch on the arm adapted to engage the projection and hold the arm open.

13. A driver for wheels mounted on an axle between the centers of a wheel lathe, comprising a support, wings thereon, a block 30 carrying a gripping jaw, fitted into the bracket between said wings, a headed bolt extending between the wings and carrying the block, there being elongated holes through which the bolt passes, a wedge engaging one of said wings and the end of the bolt opposite its head, an arm trunnioned on the block and adapted to extend between the spokes of the wheel, and an adjustable clamping part on the free end of the arm. 40

In testimony of which invention, I have hereunto set my hand, at Philadelphia, on this first day of April, 1907.

LARS H. VOLD.
